UNITED STATES PATENT OFFICE.

WILLIAM M. DWIGHT, OF DETROIT, MICHIGAN.

UNDERCUTTING-KNIFE.

SPECIFICATION forming part of Letters Patent No. 354,974, dated December 28, 1886.

Application filed March 4, 1886. Serial No. 194,028. (No model.)

To all whom it may concern:

Be it known that I, WILLIAM M. DWIGHT, of Detroit, in the county of Wayne and State of Michigan, have invented a new and useful Improvement in Undercutting-Knives, of which the following is a specification.

My invention relates to an improved knife for undercutting straight-sided grooves for use in the invention shown in my Patent No. 329,824.

Figure 1 is a side elevation of part of a planing-machine; Figs. 2 and 3, end elevations of a board, showing the straight-sided and undercut grooves. Fig. 4 is a front elevation of my improved knife and its support. Fig. 5 is a side elevation of the same, and Fig. 6 is a bottom plan view of that part of the knife at the right of line x x , Fig. 6.

1 represents part of a planing-machine, the under-surfacing cylinder of which is represented by 2, and carries two knives, 3, thereon adapted to cut straight-sided grooves in the under surface of a board passing through the machine, as shown in Fig. 2.

10 represents a post to carry my improved knife, and is to be secured to the bed of the planing-machine, or a suitable support, 5, thereon, either by being made on a shoe, 11, to be secured to the machine by a bolt, 4, or 20 in any other suitable manner.

My improved knife consists of a shank, 8, adapted to be bolted to post 10, and of such width that it will enter the groove made by knives 3, and an enlarged head, A, on the 35 end of the shank, too wide to enter said groove, and having cutting-edges 7 formed on one end thereof, and downwardly-extending wings 6, of the same width as the groove, preferably provided with cutting-edges. I usually in-

cline the cutting-edges, as clearly shown in Fig. 6, to give them a draw cut, and form the cutting-edges 7 by chamfering the ends of the head toward the center of the knife, as shown by the chamfers 12, so that the shavings made 40 by the knife will be thrown toward the center of the knife and downward. I prefer to form the cutting-edges 7 on that end of the head A which is nearest the shank 8, so that the knife will be drawn through the groove, in-

50 stead of being pushed, as this causes the shavings to pass away from the post 10, instead of

toward said post, as would be the case if the knife were pushed through the groove, and thus obviates clogging, and also enables me to make the shank 8 shorter, and causes the knife 55 to run steadier; but the cutting-edges 7 may be formed on the other end of head A and the knife pushed through the groove without departing from my invention. 9 9 represent two bolts, which hold shank 8 to post 10, and I 60 usually make shank 8 bent and secure it to the post, as shown; but this is a mere matter of mechanical convenience.

In using my invention, the shank 8 enters the groove made by knives 3 as the board is 65 fed through the machine; but the head A is too wide to enter said groove, and its cutting-edges cut out two shavings of the shape shown in dotted lines in Fig. 2, and the chamfers 12 force these shavings inward and downward, 70 so that they drop clear of the knife. The wings 6 prevent splitting of the board in advance of the knife, and also insure complete separation of the shavings, which otherwise would sometimes stick to the edges of the 75 groove.

It is evident that if it be desired to undercut only one side of a groove the head A must project only on one side of shank 8, and this modification is obvious to any mechanic. 80

What I claim as my invention, and desire to secure by Letters Patent, is—

1. A knife for undercutting a groove, consisting of the shank 8, having the laterally-enlarged head A, provided with side cutting-edges, 7, located on the end of said head adjacent to the shank, so that the latter draws the cutting-edges through the groove to force the shavings downward in advance of the head, substantially as described. 85

2. A knife for undercutting a groove, consisting of a shank adapted to enter the groove, and having an enlarged head provided with cutting-edges at one end and chamfered toward the center of the knife for throwing the 95 shavings toward the center thereof and downward, substantially as described.

WILLIAM M. DWIGHT.
